UNITED STATES PATENT OFFICE.

JOHN W. WATKINS, OF PHILADELPHIA, PENNSYLVANIA, ASSIGNOR TO DAVID LUPTON'S SONS COMPANY, OF PHILADELPHIA, PENNSYLVANIA, A CORPORATION OF PENNSYLVANIA.

SHEET-METAL WINDOW-SASH.

No. 865,834.

Specification of Letters Patent.

Patented Sept. 10, 1907.

Application filed December 31, 1906. Serial No. 350,195.

To all whom it may concern:

Be it known that I, JOHN W. WATKINS, residing at No. 2223 East York street, in the city of Philadelphia, county of Philadelphia, and State of Pennsylvania, have invented certain new and useful Improvements 5 in Sheet-Metal Window-Sashes, whereof the following is a specification, reference being had to the accompanying drawings.

My invention relates to sheet metal window sashes 10 and comprises such an organization of the sash that it may be reglazed without its dismemberment.

It comprises bounding members with continuous grooves for the sides of a series of panes, and intervening partitions between the adjacent members of said series. 15 The bounding members are permanently united within the sash, whereas the intervening partitions are removably secured in position.

It also comprehends removable means for fastening the end pane of a series in position, whereby, after said 20 fastening means is removed, the end pane may be removed.

Said intervening partitions are provided at each end with removable securing means, which may be unfastened, whereupon each intervening partition 25 may be tilted to be removed after the pane in advance of it has been removed.

Although in its present embodiment my invention is shown as applied to a window in which the panes are mounted in vertical relation with one another, it will 30 be readily understood that said invention is applicable to sashes in which the panes are mounted in horizontal relation with one another.

In the accompanying drawings, Figure I, is an elevation of a sheet metal casement window embodying my 35 invention. Fig. II, is an elevation of a sheet metal pivot window also embodying my various improvements. Fig. III, is a section taken on the line III, III, in Fig. II. Fig. IV, is a section taken on the line IV, IV, in Fig. II. Fig. V, is a section taken on the line 40 V, V, in Fig. II. Fig. VI, is a view similar to Fig. III, of a modified form of pane groove and clamp.

In said figures:—1, 1, are the side rails.

2, 2, are the bottom rails.

3, 3, are the top rails.

4, 4, are the munnions, and 5, 5, are the muntins.

The side, bottom, and top rails and the munnions may be termed "bounding members" while the elements (in this case muntins) which separate adjacent panes of a series may be termed "intervening partitions." Said 50 sash members are formed by interlocking pieces of sheet metal, only such details of construction as are pertinent to my invention being shown.

Referring to Fig. III, the body portion of the rail 3, is formed by two strips of sheet metal having flat portions 6, 6, forming the sides of the rails, together with

the moldings 9, 9, bent in the shape of an ogee curve, the metal at the lower end of this curve being then bent upwardly to form the sides 10, 10, of the pane groove, and then bent outwardly to form overhangs 11, 11, at the proper height to correspond with the pane to be 60 inserted in the window. The pane groove is closed by means of a plate or clamp 12, made of a piece of sheet metal formed by bending its edges downwardly and inwardly to fit over the overhangs 11, 11, and thereby 65 keep the sides of the pane groove in position and prevent them from spreading under the influence of heat. The plate or clamp 12, is usually made to extend over a portion of the distance between the pane supports. One of said clamps is shown in dotted lines in Figs. I and II. Its length is so proportioned to the width 70 of the panes that it may be slid to one side to provide room for the convenient withdrawal or insertion of a pane. The top of the rail is closed in the usual manner by the strip or cover 7. It will be understood that the outside configuration of this rail 3, may be varied to 75 suit different conditions.

Referring to Fig. IV, which shows the mode of securing the muntins, or intervening partitions it will be seen that the muntins 5, are provided with longitudinal extensions or flaps 13, provided with holes 14, which 80 are adapted to register with similar holes in the munnions 4. The muntins and munnions are secured together by means of screws 15, passing through the holes 14. In Fig. I, the muntins are shown as fastened to side rails 1, 1, whereas, in Fig. II, the muntins are 85 shown as fastened to side rails and munnions. These muntins bind the sash together to stop deflection by fire, yet are readily removable for reglazing the sash.

By employing the construction thus far described, it is possible to readily replace a broken pane without dismemberment of the sash; for any pane in the top row is 90 readily drawn up through the pane groove, and any intervening muntin, by the removal of the screws, may be slipped up and out of place, and thus the lower panes similarly removed.

Referring to Fig. V, the bottom rail 2, is of the usual construction except that at the top of the flat sides 16, there are short slots 17, adapted to receive tongues or flaps 18, extending from the flat faces of the munnions 4. These flaps are inserted through the slots 17, and bent 100 upwardly against the inside of the top portion or molding of the rail body thereby securely holding the munnion to the rail. At the inside of the munnion next to the pane groove are flaps 19, extending through the slots 20, at the bottom of the pane groove in the rail, said 105 flaps being also bent up to aid in securing the munnion in position. The lower face of the rail 2, is closed by the strip or cover in the usual manner.

Referring to Fig. VI, it will be seen that the body portion of the rail 3, is the same as that shown in Fig. 110

III; but the pane groove and clamp are slightly different. The lower ends of the ogee curves 9, 9, are bent upwardly to form the sides 10, 10, of the pane groove and then bent outwardly and downwardly as clearly shown to form the overhangs 21, 21, at the proper height to correspond with the pane to be inserted in the window. The pane groove is closed by means of a plate or clamp 22, made of a piece of sheet metal formed by bending its edges downwardly, inwardly and upwardly 10 as shown by the portions 23, 24, and 25, to fit over the overhangs 21, 21, and thereby keep the sides of the pane groove in position and prevent them from spreading under the influence of heat. The clamp is provided with one or more flaps 27, which may be grasped by the 15 fingers to move the clamp along the groove; it being understood that this clamp, like clamp 12, is usually made to extend over a portion of the distance between the pane supports.

In the description I have used the terms "muntin" 20 and "muntin", but in the claims I have found it convenient to use the term "uniting member" which it will be understood is intended to mean either of them.

It is to be understood that I do not desire to limit myself to the precise details of construction and arrangement herein set forth, as it is obvious that various modifications may be made therein without departing from the essential features of my invention.

I claim:

1. In a sheet metal window sash, the combination of a rail having portions bent to form the sides of a pane groove, said sides being provided with overhangs; and a sliding clamp uniting said overhangs and preventing their separation under heat, said clamp having its length so proportioned to the width of the panes of the sash as 35 to permit of its being slid to one side to provide room for the withdrawal of the pane.
2. In a sheet metal window sash, the combination with a rail having portions bent to form the sides of a pane groove, said sides being bent to form projecting overhangs; 40 and a sliding clamp engaging said overhangs for maintaining the sides of said pane groove in position, said clamp having its length so proportioned to the width of the panes of the sash as to permit of its being slid to one side to provide room for the withdrawal of a pane.
- 45 3. In a sheet metal window sash, the combination of a pair of bounding members for supporting the sides of the

panes, and provided with continuous pane grooves; means for uniting said members rigidly at each end; a series of panes; intervening partitions located between each pair of panes and removably secured to said bounding 50 members; and removable means in one of said uniting means for securing the end pane in position, whereby when said pane securing means is removed said end pane may first be removed and then the intervening partitions and panes in succession for reglazing the sash without its 55 dismemberment.

4. In a sheet metal window sash, the combination with a pair of members for supporting the sides of the panes; of means for uniting said members rigidly in the sash; a series of panes; muntins removably secured to said supporting members and located between each of the panes; and removable means in the upper uniting member for clamping the upper pane groove, whereby said clamping means may first be removed and then the panes and removable muntins in succession for reglazing the sash without 60 its 65 dismemberment.

5. In a sheet metal window sash, the combination with a pair of vertical members provided with pane grooves, and rigidly secured to upper and lower uniting members also provided with pane grooves; of a series of panes 70 separated by muntins removably secured to said vertical members; and a removable clamp for the pane groove in said upper uniting member, whereby upon removing said clamp the upper pane may be withdrawn through this groove; then by the removal of the securing means from the muntins, said muntins and the remaining panes may be removed successively without dismemberment of the sash. 75

6. In a sheet metal window sash, the combination of a pair of grooved supporting members adapted to receive a series of panes; a uniting member at the top and bottom 80 of said supporting members and rigidly secured thereto; a pane groove in the upper uniting member provided with a removable clamp for holding the sides of the groove in position and preventing them from spreading under the influence of heat; a uniting member removably secured to said supporting members between each pair of panes, whereby upon removing said clamp, the upper pane may be withdrawn through the groove in the upper uniting member, and by removing the securing means from the muntins said muntins and the remaining panes may be removed successively for reglazing without dismemberment 85 of the sash. 90

In testimony whereof, I have hereunto signed my name, at Philadelphia, Pennsylvania, this 28th day of December, 1906.

JOHN W. WATKINS.
